(57) **CLAIM**

The ornamental design for an optical fiber management bracket, as shown and described.

DESCRIPTION

This application is related to co-pending design patent application Ser. No. 29/426,356, entitled "Optical Fiber Management Cassette" filed on Jul. 3, 2012, and to non-provisional patent application Ser. No. 13/541,419, entitled "Optical Fiber Connectivity Management System" also filed on Jul. 3, 2012.

FIG. 1 is a perspective view of an optical fiber management bracket that forms our new design;

FIG. 2 is another perspective view of an exemplary embodiment thereof in an alternate position of use;

FIG. 3 is a front elevational view thereof;

FIG. 4 is a back elevational view thereof;

FIG. 5 is a bottom plan view thereof; and,

FIG. 6 is a side elevational view thereof.
